REFRIGERATION APPARATUS

Edwin S. Pridham, Oakland, Calif.

Application May 31, 1932, Serial No. 614,322

Renewed January 15, 1935

5 Claims. (Cl. 62—90)

My invention relates to refrigerating apparatus, and more specifically to such apparatus in which evaporation of a fluid at atmospheric pressure produces the cooling effect.

5 Among the objects of my invention are: To provide a system in which an efficient loss of heat will occur; to provide means for providing a large area of evaporating surface; to provide a circulating refrigerating system in which the heat exchanger and cooler are separate units; and to provide a refrigeration system which is simple in construction, economical to manufacture, durable and efficient in use, and which permits of attaining a low humidity in the interior of the 15 refrigerator box.

Other objects of my invention will be apparent or will be specifically pointed out in the description forming a part of this specification, but I do not limit myself to the embodiment of my invention herein described, as various forms may be adopted within the scope of the claims.

Referring to the drawing:

Figure 1 is a longitudinal sectional view of a preferred type of my refrigeration system.

25 Figure 2 is a cross sectional view through the heat exchanger shown in Figure 1 on the line 2—2.

Figure 3 is a longitudinal sectional view of the top portion of an alternative form of heat exchanger.

30 Figure 4 is a cross sectional view of the heat exchanger as shown in Figure 3, and taken on the line 4—4.

The principle upon which the invention is 35 based is that of cooling by the evaporation of a volatile fluid. The degree of cooling will be dependent upon the difference in temperature between the wet and dry bulb thermometers, and the device will be most efficient in hot dry climates, where a cooler is most desirable. Crude 40 forms of coolers using the above principle are exemplified by the porous Mexican ollas for cooling water, and the wet burlap mountain type cooler which is well known in the art.

45 Broadly speaking my invention comprises a circulating liquid refrigeration system which is divided into two portions. One portion is on the interior of a chamber to be cooled, and the other portion is a heat exchanger. This portion 50 of the system is provided with a convoluted surface covered with fluid absorbent material and this material kept saturated with a volatile fluid. The fluid is then evaporated rapidly by causing a current of air to move past the absorbed fluid 55 in the fabric on the convolutions of the heat ex-

changer. Heat transference from the liquid in the circulating system is rapid due to the use of metals having good heat conductivity in the heat exchanger.

In Figure 1 a circulating system 1, preferably 5 built up from pipe, has a cooling coil section 2, and a heat exchange section 4. This forms a closed system and is filled with a liquid, preferably water or brine. The cooling coil is contained in a refrigerator box 5, which is provided 10 with a removable top cover 6. While I have shown a top opening box, it will be apparent that the cooling coil may be so arranged inside the box that a side door can be used. The refrigerator box is preferably double walled and the space 15 between the walls filled with a good heat insulator such as ground cork or asbestos wool. Box legs 7 serve to raise the cooling chamber from the floor.

The heat exchange portion of the system is 20 preferably a casting of a metal having high heat conductivity such as copper or aluminum, and is preferably provided with integral fins 9 as shown in Figure 2. The center of the heat exchanger is preferably bored out to form an interior straight and smooth tube 10. Couplings 11 and elbows 12 serve to connect this straight portion to the system 1. Unions 14 are provided so that the two units may be easily disconnected if desired.

An alternative form of heat exchanger is 30 shown in Figure 4, and here the central bore is connected to the hollow fins 15. These fins are provided with seepage holes 16 of small diameter 35 extending through the fin walls and connecting the interior of the heat exchanger with the outside.

In both forms of heat exchangers the fins are 40 covered with absorbent fabric 17 such as coarse linen, burlap or canvas. When solid fins are used 45 holes 19 are preferably provided in the fin structure to permit air circulation through the fabric.

The entire heat exchanger is surrounded by a 50 casing 20 which not only supports the structure, but acts as a flue to confine air to the space occupied by the heat exchanger. The bottom portion 21 of this casing is preferably formed into a cone shape and provided with a drain pipe 22 to carry off accumulated unevaporated fluid.

The bottom portion 21 of the casing may be 55 solid as shown, and air supplied to the casing by blower 24, or, it may be perforated, and the draft of air created through the casing by chimney action.

A tank 25 smaller in diameter than the casing, is supported on the top of the casing 20 by brackets 26, and the bottom of the tank is perforated with small drip holes 27. A supply of 5 volatile liquid, preferably water, on account of its availability and cheapness, is provided by a faucet 28 in connection with the water main 29.

When the hollow fin form is used as shown in Figure 4, the tank 25 is not perforated, but 10 is connected directly to the circulating system as shown at 30. This allows water from the tank to supply the loss of water through the seepage holes 16 in the walls of the hollow fins 15.

Casing 20 and cooperating structures are 15 mounted on casing legs 31, which serve to raise the heat exchange structures off the floor.

In operation water is admitted to the tank and drips onto the fabric mounted on the fins, and is absorbed by the fabric. The air moved 20 through the casing either by draft or by the blower as shown, evaporates the absorbed water and the temperature of the fabric is reduced to that of the wet bulb thermometer. This fabric being in intimate contact with a good heat 25 conductor, cools the fins, and also abstracts heat from the water or brine in the system. The liquid thus cooled becomes heavier than that in the uncooled portion of the system and a circulation will be started through the exchanger 30 downward and into the cooling chamber. Here the liquid will pick up heat from the articles inside, and the liquid thus warmed will rise to the top of the cooling coil and pass back to the top of the heat exchanger, thereby creating 35 a continuous circulation of liquid in the system.

The drip of water from the tank is preferably adjusted to cover the fabric on the entire surface of the fins, and to supply just enough to 40 allow for the evaporation.

In the hollow fin type of heat exchanger water from the system will seep through the holes in the fin walls and saturate the fabric. The 45 pressure in the supply tank may then be regulated to supply just enough water to the fabric.

While the temperature drop is dependent on the difference between the wet and dry bulb 50 readings of the thermometer, the amount of space than can be lowered to the wet bulb temperature will depend on the area of evaporative surface. A large space may be cooled by my invention with a small heat exchanger because of the rapid evaporation and efficient 55 heat transfer.

While the preferred form of my invention shows a blower to move the air, it will be obvious that in localities where power is not avail-

able, any of the known means of moving air may be used, such as flue action, or the providing of funnels facing the prevailing wind such as are used on ship board.

As an example, with an air temperature of 80° 5 with a humidity of 30 per cent, the temperature of the refrigerator box may be reduced 20° and even lower with lower humidities.

I claim:

1. A heat exchanger for a circulating refrigeration system which comprises a tube of high heat conducting material, a fin integral with said tube, a layer of fluid absorbent material on said fin, said fin having ducts connecting said tube with said fluid absorbent material. 15

2. A heat exchanger for a circulating liquid refrigeration system which comprises a conduit of high heat conductivity, fins integral with said conduit extending longitudinally along said conduit, a layer of fluid absorbent material on said 20 fins, means for supplying a volatile fluid to said material, an enclosure for said conduit and fins, and means for passing a current of air through said enclosure and between said fins in a direction opposite to the circulation of liquid in said 25 refrigeration system.

3. In combination with a circulating fluid refrigeration system, a heat exchanger comprising a tubular conduit for said fluid, fins on said conduit, said conduit and said fins being formed 30 of a metal having a high heat conductivity, a fluid absorbent material on the outer surface of said fins, said fins having apertures therein for conveying said fluid to said fluid absorbent material. 35

4. In combination with a circulating fluid refrigeration system, a heat exchanger comprising a tubular conduit for said fluid having a smooth interior duct and a corrugated external surface, said conduit being formed of a metal 40 having high heat conductivity, a layer of liquid absorbent material on said corrugated surface, and means for cooling said conduit by the evaporation of a volatile fluid from said liquid absorbent material. 45

5. A heat exchanger for a circulating refrigeration system which comprises a tube of aluminum, an aluminum fin integral with said tube, a layer of fabric on said fin, said fin having ducts connecting the interior of said tube with 50 said fluid-absorbent material, and means for passing a current of air through said fin to evaporate fluid therefrom, said ducts being of a size sufficient to supply fluid from the interior of the tube to said fabric at a rate at least equal 55 to the evaporation rate.

EDWIN S. PRIDHAM.
